UNITED STATES PATENT OFFICE.

J. H. MERRIAM, OF BOSTON, MASSACHUSETTS.

STENCIL-PALETTE.

Specification of Letters Patent No. 19,943, dated April 13, 1858.

To all whom it may concern:

Be it known that I, JOSEPH H. MERRIAM, of Boston, in the county of Suffolk and State of Massachusetts, have invented a new and 5 useful Palette for Stencil-Markers or for Painters' Use; and I do hereby declare that the same is fully described and represented in the following specification and the accompanying drawings, of which—

10 Figure 1, is a side view, Fig. 2, a top view, and Fig. 3, a transverse section of such invention.

For spreading ink or paint or preparing a brush with the requisite amount of such 15 for marking by a stencil plate it has been customary to make use of a flat piece of board or palette or plate of tin or other suitable metal. On this a few drops or a small quantity of the liquid ink or paint is thrown. 20 and with the marking brush it is rubbed and spread over the surface of the board or palette until a sufficient quantity has been taken up in the brush to enable it to be rubbed over the stencil plate. Under such circumstances 25 the paint or liquid has been taken from a vessel entirely separate from the palette, board or slab.

The nature of my invention consists in a combination of a flexible slab or palette, a 30 vessel or reservoir for holding the ink or paint and a pipe or its equivalent, so applied to the slab or palette and made to extend into the reservoir, that on pressure being made on the outer surface of the palette or slab or 35 any elastic or flexible part of it, ink or paint may be forced from the reservoir through the tube and upon the outer surface of the palette or slab. Thus in case, a stencil marker is desirous of increasing the supply 40 of ink or paint on his palette, he has only to press with his brush on the palette, in which case, the flexible palette acting on the air within the vessel or reservoir, will cause such to press on the surface of the liquid so as 45 to produce an escape out of the reservoir and upon the palette, of a portion of the liquid contents of the reservoir. By my invention, the liquid in the reservoir is prevented from evaporation, and even should 50 the palette be overturned, little or none of the liquid will be spilled out of it.

In the drawings, *a*, *a*, exhibits a flat flexible or elastic plate made of tinned iron or other suitable material and forming the top of a shallow reservoir, *b*, which if desirable 55 may be provided with a handle, *c*. Such reservoir should have a filling hole or mouth, *d*, furnished with a stopper, *e*, which may screw into it or be otherwise applied so as to fit closely and air tight. At the middle 60 part of the palette or plate *a*, and extending down within the reservoir, is a small tube *f*, which is, at one end, fastened to the flexible plate, and terminates at its lower end, at a short distance above the bottom of the reservoir, the tube being open at both ends and through the slab or palette, *a*. A helical spring, *g*, may surround the tube and extend from the bottom to the top of the reservoir, and so as to aid in restoring the plate 70 to its normal position after pressure has been made on it.

The flexible palette combined with the reservoir and the pneumatic pressure tube renders my invention of great convenience 75 and utility to painters as well as to stencil markers.

I am aware that an inkstand has been made with a cup and reservoir combined with a pneumatic tube and a flexible or elastic diaphragm so arranged that on pressing the cup and tube downward, the ink or liquid of the reservoir would be caused to flow upward into the cup. This however, although somewhat analogous to my invention, I do not claim, as it differs materially therefrom, inasmuch as the latter containing a flat slab or flexible palette suitable for preparing the brush for the stencil plate, whereas, no such device is found in the inkstand. 90 The two inventions belong to separate branches of art.

What I do claim as my invention, or as a new manufacture, is—

A stencil marker's palette or pot constructed substantially as described.

In testimony whereof I have hereunto set my signature.

JOS. H. MERRIAM.
